(57) **CLAIM**

The ornamental design for a “culinary whisk”, as shown and described.

DESCRIPTION

FIG. 1 is a front perspective view of a “culinary whisk” showing my new design;

FIG. 2 is a perspective view in alternative configuration thereof;

FIG. 3 is a front view thereof;

FIG. 4 is a rear view thereof;

FIG. 5 is a side view thereof;

FIG. 6 is an opposite side view thereof;

FIG. 7 is a top view thereof; and,

FIG. 8 is a bottom view thereof.

The part of the “culinary whisk” shown in phantom lines depicts the environment of my new design and forms no part of my design.
